ROBERT R. KECK, OF ALHAMBRA, CALIFORNIA.

HAND-CONTROL LOAD-LIFTING TRUCK.

Application filed March 14, 1923. Serial No. 625,106.

To all whom it may concern:

Be it known that I, ROBERT R. KECK, a citizen of the United States, residing at Alhambra, in the county of Los Angeles and 5 State of California, have invented certain new and useful Improvements in Hand-Control Load-Lifting Trucks, of which the following is a specification.

This invention, which generally relates to 10 hand manipulated trucks adapted to move articles of furniture, filing cabinets, book cases and other articles which stand on legs of sufficient height to permit of running the truck thereunder, is more especially designed 15 for lifting and transporting the modern types of gas and electric stoves. Primarily my invention has for its object to provide an improved truck of the general character mentioned, that is of a relatively simple and 20 inexpensive construction, whose portable framing is practically adjustable to set the lifting elements to suit the body heights of the stove or other article to be lifted and in which the operation of lifting or lowering 25 the stove, or other object to be received thereon, is effected by a simple arrangement of and an easily controlled hand lever.

Another object of my invention is to provide an improved construction of truck for 30 the purposes stated in which the parts are compactly assembled and arranged for providing a truck of great strength and the said parts thereof joined that they will not 35 easily break or get out of operative condition, even when under great load strains.

With the above objects in view, my invention is a combined load lifting and transferring truck embodying the peculiar features of construction and novel combination 40 of parts fully explained in the following detailed description, specifically mentioned in the appended claims and illustrated in the accompanying drawing, in which:—

Figure 1 is a perspective view of my improved construction of truck, the load supporting elements being shown at the lifted position.

Figure 2 is a longitudinal section thereof, the parts being positioned as in Figure 1 in 50 dotted lines and at the lowered position in full lines.

Figure 3 is a detail vertical cross section

of the truck looking in the direction of the operating lever, the parts being shown in the 55 lifted position.

Figure 4 is a detail view showing the truck handle swung back in dotted lines.

My improved truck comprises essentially a main or supporting frame that is mounted on rollers to facilitate pushing or pulling 60 the truck with or without the load, as desired, vertically shiftable lifting elements mounted on the main or supporting frame and a single hand lever control means to govern the maximum leverage for lifting the 65 load and holding it to its lifted position without undue exertion on the part of the operator handling the truck.

In the practical development of my invention, as shown in the drawing, the main 70 or supporting body includes an upper rectangular frame that consists of opposite side bars 1—1 and opposite end bars 2—2. The main body frame is supported at the four corners by pipe legs 3—3 whose upper ends 75 are joined with the corners of the main body members, in any suitable manner, and to provide for adjusting the main frame, high or low, as desired, each corner support or leg 3 includes a caster carrying pipe section 30. 80 The several pipe sections 30 slidably engage their respective tubular pipe legs 3 and are secured in their vertical adjustment by clamp screws, as will be readily understood from the drawing.

85 The main or body frame also includes bottom side and bottom end members 4—4 and 5—5 secured at their ends to the pipe legs 3.

Rigidly mounted on the body frame is a supplemental frame, which is located at the 90 forward end of the main frame and comprises a vertical member 6 that is rigidly connected at its upper and lower ends to the upper and lower front bars of the main or body frame, and a horizontal brace bar 7 that 95 extends from the front to the rear bottom members 5—5.

The supplemental frame also includes an inwardly extended horizontal member 8 that is riveted or otherwise made fast to the central member 6 and to the upper end of a short vertical standard 9. The standard 9 has its lower end secured to the bottom bar 7 and it is laterally braced by diagonally ex-

tended side members 10—10 whose lower or outer ends are riveted to the opposite side bars 4—4 of the main frame, as shown.

In my truck structure, the lifter frame is 5 also of rectangular shape and is substantially of the length and width of the upper rectangular frame and of the main supporting frame or body, it being shaped for fitting closely within the confines of the sides and 10 ends of the top main frame portion when the said lifting elements are at the lowered position, as shown in Figure 3.

The lifter frame consists of opposite side members 11—11 and opposite end members 15 12—12, the latter and the members 11—11 being secured at the corners to produce a frame that is sufficiently rigid to support the load when lifted to the position shown in Figure 1, it being understood that when the 20 lifter frame is at the lowered position it rests upon the top of the main frame to thereby permit of freely moving the truck frame under the object to be lifted and moved.

25 The outer ends of the side bars 11—11 of the lifter frame each have an elongated slot 11^a and said slots are provided to receive studs 14—14 secured to the upper ends of the opposite pairs of U-shaped lever frames 30 located one at each end of the main frame, as is best shown in Figure 1, by reference to which it will be observed each frame includes opposite side arms 13—13, which are joined at their inner ends by a cross member 15 and 35 to each of which, centrally thereof, is pivotally connected a pendent link 16, the purpose of which will be presently explained.

40 Each lever frame is pivotally mounted on the top of the main frame to swing in the vertical direction and for such purpose each 45 of the opposite side arms 13 of the frame has a lateral stud 13^a located near the outer end thereof for engaging bracket bearings 13^b—13^b attached to and projected from their adjacent top side rails 1—1 of the main frame, as shown.

50 17 designates a main lever bar which extends inwardly and lengthwise of the main frame and it is fulcrumed on a stud 17^a that projects laterally from the meeting ends of the members 8 and 9 of the supplemental frame.

55 By referring particularly to Figure 2 of the drawing it will be seen the outer end of the main lever bar 17 is pivotally joined to one end of a substantially U-shaped lever link 18. The other end of said link is pivoted as at 19 to the bifurcated end of the bell crank lever 20 that is fulcrumed to the vertical 60 frame member 6 and has its outer end provided with a handle 21 for conveniently changing the position of the lever 20 when shifting the lifting element up or down, as will be presently further explained.

65 By reason of pivotally joining the link 18

and lever 20 as at 19, the said link and lever are caused to swing in the same plane of movement so that, when the parts are positioned as shown in dotted lines in Figure 2, the link 18 will rest upon the said lever 20 as shown to form a substantial locking of the parts in the position mentioned in a manner later explained.

22 designates a bail shaped handle whose opposite side members are pivoted to the outer front ends of the main frame. The handle 22 when swung out, as indicated in Figures 1 and 2, serves as a hand control for pulling or pushing the truck with the load as desired, and when the truck is not in use, the said handle 22 can be swung back on top of the main frame, as is clearly indicated in dotted lines in Figure 3.

75 The two links 16—16 pendent from the adjacent inner cross members 15 of the swinging frames are pivotally connected to the inner end of the main lever 17 and by reason thereof when the said main lever is swung up or down the two swinging frames are 80 likewise shifted, it being understood, from the drawing, that the pivotal connection of the said two frames are such that when the main lever is swung down in the manner presently mentioned, to the position shown 85 in Figure 1 and indicated in dotted lines in Figure 2, the outer ends of the frames are 90 swung up and thereby elevate the rectangular lifting frame with the stove thereon and with the legs of the said stove raised from the floor, it being understood that the stud and slot connections 11^a and 14 that join the lifter frame and the side arms of the swingable lever frames provide for the necessary shifting of the said members when adjusting the parts, as stated.

95 100 105 By reason of providing a bell crank hand lever and fulcruming the said lever on the vertical frame member 6 and joining the said bell crank lever to the outer end of the main lever 17 by a substantially U shaped link connection, as shown and described, 110 when the said crank lever is swung up with the handle close against the upper end rail of the main frame, as in Figure 2, the U shaped link connection, joined with the bell crank lever and the main lever 17 causes the outer end of the said lever 17 to swing downwardly and since the inner end of the said lever 17 connects, through the links 16—16 115 with the two swinging frames, the said frames are swung so they assume the horizontal position, practically flush with the top rails of the main frame, the fulcrum connections for the bell crank lever or U shaped links and the outer end of the levers 17 being such that when the swinging frames are 120 shifted to the said horizontal position, the several levers will be held in a substantially locked position to hold the said swinging 125 frames up to the position stated and there- 130

by permit of the ready removal of the truck from under the object that has been lifted and moved to the desired place.

After the truck is pushed under the stove or other object to be loaded and shifted, the said object is lifted from the floor by grasping the hand hold of the lever 20 and pulling it down to the inverted vertical position shown in Figure 1 and dotted lines on Figure 2, the movement of the several levers pulls the inner ends of the swinging frames down and lifts their outer ends to cause the said frames to rise above the main frame and thereby lift the stove or other object to be moved. When the parts are adjusted to the last stated position the weight of the load tends to hold the several levers, including the hand control or crank lever, locked against movement until a pull strain is applied at the hand hold end of the crank lever.

From the foregoing description taken in connection with the drawing, the complete construction, the manner of operation and the advantages of my invention will be readily apparent to those familiar with the making and using of trucks of the general character explained.

Only the manipulation of a single hand lever (the bell crank lever 20) is necessary, in my invention, to shift the lifting elements to the high or low positions and for holding them to such positions until sufficient force is applied to pull out the hand lever from either of its reversed positions, thus making it possible for a single operator, with slight effort, to move the stove or other heavy object unaided.

What I claim is:

1. A combined object lifting and transferring truck comprising a main frame including horizontal opposite sides and end members, a lifter frame that works inside the said top members of the main frame, a pair of vertically swingable frames, the said frames being pivotally mounted, one at each end of the top side members of the main frame, the lifter frame being connected to and movable up or down with the outer ends of the swingable frame, a main vertically swingable lever whose outer end extends to the front end of the truck frame, connections that join the inner end of the lever to the inner adjacent ends of the two swingable frames to thereby raise and lower the lifter frame as the main lever is swung up or down and hand controlled lever connections joined with the truck frame and the main lever for effecting movement of the main lever, the said connections including members adapted for holding the parts stated to their reversed adjustments when the main lever is shifted in reverse directions.

2. In a truck of the character stated, a

main truck frame including top, side and end rails, a lifting frame centrally movable above the said top and side rails of the main frame, actuating means for raising and lowering the lifter frame, the said means comprising a pair of oppositely disposed swingable frames, each of said frames being fulcrumed between its respective portion of the top side rails of the main frame, a main lever bar fulcrumed on the truck frame and extended lengthwise therethrough from the front end thereof, connections that join the adjacent end of the swingable frames to the lever, a bell crank hand lever fulcrumed on the forward end of the truck frame, and a link connection pivotally joined to the inner end of the bell crank lever and the outer end of the main lever bar, the fulcrum connections of the main lever or hand lever and the link being positioned for maintaining the parts in a relatively locked condition when shifted to their reverse adjustments for raising and lowering the lifter frame.

3. In a truck of the character stated, a main truck frame including top, side and end rails, a lifting frame centrally movable above the said top and side rails of the main frame, actuating means for raising and lowering the lifter frame, the said means comprising a pair of oppositely disposed swingable frames, each of said frames being fulcrumed between its respective portion of the top side rails of the main frame, a main lever bar fulcrumed on the truck frame and extended lengthwise therethrough from the front end thereof, connections that join the adjacent end of the swingable frames to the lever, a bell crank hand lever fulcrumed on the forward end of the truck frame, a link connection pivotally joined to the inner end of the bell crank lever and the outer end of the main lever bar, the fulcrum connections of the main lever or hand lever and the link being positioned for maintaining the parts in a relatively locked condition when shifted to their reverse adjustments for raising and lowering the lifter frame, the actuating or swinging frames and the lifting frame having compensating connection to provide for elevating the lifter frame in the horizontal plane as the actuating frames swing on their pivotal connections.

4. An object lifting and moving truck comprising a main frame which includes horizontal opposite side and end members, a like shaped lifter frame, a pair of opposing and longitudinally disposed lever frames, each of the said lever frames being pivotally mounted on its respective end of the opposite side members of the main frame for projecting the outer ends thereof above the main frame when their inner ends are moved downwardly, the lifter frame being connected to the outer ends of the opposite pair of lever frames to move up and down with such

frame ends, a main lever projected in the longitudinal direction of the main frame, connections that join the inner ends of both pivoted frames to the inner end of the main lever, a single hand control lever fulcrumed on the main frame for being swung vertically to reverse positions against the main frame and a link connection which joins the

hand control lever to the outer end of the main lever, the fulcrums of the several levers and the link connection being such that when the hand lever is swung down the link and lever interengage and are held in a relatively locked position.

ROBERT R. KECK.
